HURDLE

Sebastian J. Marzucco, Wynnewood, Pa.

Application June 8, 1949, Serial No. 97,784

5 Claims. (Cl. 272—59)

1

This invention relates to a hurdle and more particularly relates to a hurdle which can be utilized commonly on a cinder track for the running off of various hurdling events in a track meet.

As is well known in running off a track meet, hurdling heights of thirty inches, thirty-six inches and either thirty-nine or forty-two inches are normally required. Generally speaking, it is conducive to the rapid handling of the hurdling events to have a single hurdle which is capable of providing the plurality of hurdling heights required.

Where a single hurdle is utilized to provide the various necessary hurdling heights, it is necessary to provide means to compensate for the increased height of the hurdle bar so that the resistance to upsetting when the hurdle bar is struck by the hurdler will remain substantially constant. The means heretofore used to accomplish thus purpose have been troublesome in that they all rely on proper adjustment of the compensating means by the person tending the hurdle. As it is human to err, particularly when speed is a requisite such as here, it has been found that the compensating means are frequently not properly adjusted for an increase in the height of the hurdle bar and an injustice is, therefore, done to the participants in the race.

As indicated above, one of the major problems with respect to running off hurdling events is the problem of handling the hurdles with rapidity and a minimum of manpower. In this regard, a major delay results incident to the time necessary to pick up hurdles which have been upset by the runners. It is, therefore, apparent that a hurdle which, after being upset, would right itself would greatly facilitate the speedy handling of hurdling events.

It is, therefore, an object of this invention to provide a hurdle which can be set at varying heights.

It is a further object of this invention to provide a hurdle which can be set at varying heights having means to automatically compensate for the changes in elevation of the hurdle bar so that the hurdle bar offers a substantially constant resistance irrespective of its position.

A still further object of this invention is to provide a hurdle which has a hurdle bar mounted so that it can be positioned at various heights and having securing means for the hurdle bar mounting which will securely hold the mounting in the desired position and yet permit the mounting to be moved with ease to another position.

2

An additional object of this invention is to provide a hurdle which is self-righting.

An additional object of this invention is to provide a hurdle which, while providing the proper resistance to upsetting by a hurdler, will drop rapidly after the requisite upsetting force has been applied, thus conducting to the prevention of knee and ankle injuries of the so-called follow leg of the runner.

These and other objects of this invention will become apparent on reading the description in connection with the following drawings, in which:

Figure 1 is a side perspective view of a hurdle in accordance with this invention;

Figure 2 is a section taken on a vertical plane through the center of one of the support members of the hurdle of Figure 1;

Figure 3 is a sectional view taken on the horizontal plane indicated by the line 3—3 in Figure 1 and showing the locking mechanism in full;

Figure 4 is a section taken on the vertical plane indicated by the line 4—4 in Figure 1; and

Figure 5 is a horizontal section taken on the plane indicated by the line 5—5 in Figure 1.

As shown in the figures, a hurdle 2 in accordance with this invention comprises a pair of spaced hollow support members 3, each having a normally horizontal portion 4 and a normally vertical portion 6 connected by a curved portion 8. Each support 3 is preferably made from a single tube of a light metal, for example, aluminum, bent to shape. A tubular support member 10 passes through openings 12 in upper portions 6 of the supports and abuts against the interior surfaces of the upper portions 6 of the supports, respectively (see Figure 5).

Tube 10 is secured in place by rivets 14 which pass through the upper portions 6 and tube 10. A second tube 16 passes through openings 18 in the lower portion of the supports, respectively, and is similarly secured to the lower portions. The tubes 10 and 16 act to secure together and brace the support members.

The lower portions 4 of the support members are, respectively, plugged with weighted plugs 20. The plugs 20, it will be apparent, provide resistance to upsetting of the hurdle 2.

A pair of tubular members 22 are telescoped over the upper portions 6 of the supports, respectively. The upper end of the members 22 are flattened, as indicated at 24, and have a hurdle bar 26 secured thereto by sheet metal screws or any other convenient conventional means.

Means in each support to secure the tubular members 22 each comprise oppositely disposed

balls 28 which are carried in a tube 30 and biased outwardly by a compression spring 32 within tube 30. A tube 30 is secured by a pressed fit in openings 34 in the upper portion 6 of each support. Each member 22 has a plurality of openings 36 which are adapted to be brought into register with balls 28. As illustrated in Figure 4, openings 36 are preferably chamfered so as to cam balls 28 inwardly with greater facility.

Each support houses identical means to compensate for changes in the elevation of the hurdle bar so that the hurdle bar will offer a substantially constant resistance irrespective of its position. Each compensating means comprises a bar 38 secured between the upper flattened end of the member 22 and leading downwardly into the upper portion 6 of the support. The lower end of each bar 38 carries a hook 40 to which is secured a cable 42.

Cable 42 leads upwardly around tube 30, then downwardly around tubes 18 and 16 to a hook 44 secured to weight 46. Weight 46 is adapted to slide within the lower portion 4 of the support. Weight 46 is biased towards plug 20 by a compression spring 48 which is interposed between weight 46 and tube 16.

In operation, the hurdle rests on the lower portions 4 of the supports. The hurdle bar 26 may be positioned at the desired height by exerting an upwardly or downwardly directed force on the hurdle bar as is appropriate. Thus, for example, if the hurdle were as shown in Figure 1 and it were desired to raise hurdle bar 26, it would only be necessary to grasp the center of the hurdle bar with one hand and pull upwardly. The upward pull would result in the inward camming of balls 28 against springs 32 by openings 36 in members 22. When the balls 28 register with the openings corresponding to the desired height of the hurdle bar, the balls 28 will enter these appropriate openings 36, thus securing the hurdle bar at the desired height. This spring biased ball securing means eliminates the time consuming necessity for operating the conventionally used devices for securing the hurdle bar at the desired height.

Observing particularly Figure 2, it will be apparent that, as the hurdle bar 26 is elevated, the bars 38 secured to member 22, respectively, will be pulled upwardly out of upper portion 6 of the supports thus providing slack in cables 42. This slack in cables 42 is taken up, respectively, by the sliding of weights 46 towards plugs 20 by means of springs 48. Correspondingly as the hurdle bar is lowered, cables 42 will slide weights 46 away from plugs 20 against springs 48.

Considering now a force striking hurdle bar 26, as, for example, the hurdler's leading foot, it will be apparent that the higher the hurdle bar 26 is located the greater will be the turning moment of the force being exerted. It will be noted that the weight 46 is positioned to exert a turning moment in opposition to that of the above considered force exerted against the hurdle bar. It will further be noted that, as the hurdle bar is elevated and the turning moment exerted by the above considered force is correspondingly increased, the weight 46 is moved to the left so as to exert a correspondingly greater turning moment in opposition to the first mentioned turning moment. Similarly, when the hurdle bar is lowered, the weight is carried to the right, decreasing the opposing turning moment which it exerts. Thus the resistance offered by hurdle bar 26 is maintained substantially con-

stant irrespective of the height of the bar. In actual practice the preferred resistance is eight pounds.

An observation of the structure of the illustrative hurdle will make it clearly apparent that it is self-righting. The necessary weights in lower portions 4 of the supports requisite to provide the necessary resistance to upsetting is provided largely by plugs 20 and movable weights 46. These weights make lower portion 4 considerably heavier than the combined weight of the upper portion 6 of the support and members 22 together with hurdle bar 26. When the hurdle has been knocked down so that members 22 rest on the track, the turning moment exerted by lower portion 4 of each support including plugs 20 and weights 46 is sufficient to cause the hurdle to be rotated about curved portions 8 and righted.

It will be understood that the above described hurdle is merely illustrative and that applicant does not desire to be limited except as set forth in the following claims.

What is claimed is:

1. A hurdle comprising a pair of spaced hollow supports each having a substantially vertical upper portion and a substantially horizontal lower portion, a pair of members telescopically mounted on the upper portions of said supports, a hurdle bar secured to said members, means to adjustably secure said members to the upper portions of said supports, an arm depending from one of said members into one of said supports, a fixed member in the upper portion of the support into which said arm depends, a movable weight within the horizontal portion of said support into which said arm depends, resilient means biasing said weight away from said arm, and non-extensible flexible means connected to said weight and the lower portion of said arm, said flexible means passing over said fixed member.

2. A hurdle comprising a pair of spaced hollow supports each having a substantially vertical upper portion and a substantially horizontal lower portion, a pair of members telescopically mounted on the upper portions of said supports, a hurdle bar secured to said members, means to adjustably secure said members to the upper portions of said supports, an arm depending from one of said members into one of said supports, a fixed member in the upper portion of the support into which said arm depends, a movable weight within the horizontal portion of said support into which said arm depends, resilient means biasing said weight away from said arm, and a cable connected to said weight and the lower portion of said arm, said cable passing over said fixed member.

3. A hurdle comprising a pair of spaced hollow supports each having a substantially vertical upper portion and a substantially horizontal lower portion, a pair of members telescopically mounted on the upper portions of said supports, a hurdle bar secured to said members, means to adjustably secure said members to the upper portions of said supports, an arm depending from each of said members into each of said supports, a fixed member in the upper portion of each of said supports, a movable weight within the horizontal portion of each of said supports, resilient means biasing each weight away from each of said arms respectively, and non-extensible flexible means in each of said supports connected to said weights and the lower portions of said arms,

said flexible means passing over said fixed members in said supports.

4. A hurdle comprising a pair of spaced hollow supports each having a substantially vertical upper portion and a substantially horizontal lower portion, a pair of members telescopically mounted on the upper portions of said supports, a hurdle bar secured to said members, means to adjustably secure said members to the upper portions of said supports, an arm depending from each of said members into each of said supports, a fixed member in the upper portion of each of said supports, a movable weight within the horizontal portion of each of said supports, resilient means biasing each weight away from each of said arms respectively, and a cable in each of said supports connected to said weights and the lower portions of said arms, said cables passing over said fixed members in said supports.

5. A hurdle comprising a pair of spaced hollow supports each having a substantially vertical upper portion and a substantially horizontal lower portion, a pair of members telescopically mounted

on the upper portions of said supports, a hurdle bar secured to said members, means to adjustably secure said members to the upper portions of said supports, a movable weight within the horizontal portion of each of said supports, resilient means biasing each weight away from each of said upper portions respectively, and means connecting said members and said weights for moving said weights away from said vertical portions as said hurdle bar is raised to maintain the resistance of said hurdle to overturning substantially constant irrespective of the position of said hurdle bar.
